UNITED STATES PATENT OFFICE.

KENNEDY DOUGAN, OF MINNEAPOLIS, MINNESOTA.

STEAM-PUMP OR AIR-COMPRESSOR.

1,183,175.

Specification of Letters Patent.

Patented May 16, 1916.

Application filed January 16, 1909. Serial No. 472,668.

To all whom it may concern:

Be it known that I, KENNEDY DOUGAN, a citizen of the United States, and resident of Minneapolis, in the county of Hennepin and State of Minnesota, have invented certain new and useful Improvements in Steam-Pumps or Air-Compressors; and I do hereby declare the following to be a full, clear, and exact description of the invention, such as will enable others skilled in the art to which it appertains to make and use the same.

The object of this invention is to provide a direct acting steam pump or air compressor in which steam may be expanded in such a manner that the efficiency will be equal to that of the best type of fly-wheel steam pump or air compressor.

A further object is to provide a direct acting pump or air compressor that will occupy small floor space, and be of comparatively cheap construction, and as compared with other direct acting pumps, will operate without jar or shock.

25 In the machine herein disclosed, the pistons start gradually, acquire velocity, and come to rest gradually.

In common pumps without fly-wheels the pistons are moving at full speed to the end 30 of their stroke, which requires them to be checked suddenly, causing undesirable vibrations. In the invention herein disclosed, steam is admitted to the steam cylinder at boiler pressure and automatically cut off at 35 the required point to carry the piston to the end of its stroke. At the beginning of said stroke and up to the point in the stroke where the entire steam pressure on the piston falls, until it only equals the entire re- 40 sisting pressure on the water or air piston, the excess of energy in the steam end is expended in giving velocity to a heavyweight, connected to the piston rod. The energy thus stored is given out in useful effect in 45 finishing the stroke.

In the accompanying drawings—Figure 1 is a vertical longitudinal section of a direct acting steam pump, disclosing the essential feature of the invention, a part of 50 the water end being broken away; Fig. 2 is a vertical cross-section, on a reduced scale, taken on line *a*—*b* of Fig. 1.

1 designates, as a whole, the steam cylinder, having the admission ports 2 and 3, and the exhaust ports 4 and 5. Preferably, two 55 separate and independent admission valves are employed, being steam-actuated and having respective pilot valves in housings 6 and 7.

8 and 9 indicate projections on the stems 60 of the pilot valves, adapted to be engaged by valve operating devices 50 and 51.

Before completing a description of the steam apparatus, the salient feature of the construction will be described. This consists of a heavy weight, 10—12, secured to the piston rod 13 but supported in such a way that no part of its weight is borne by said rod. As shown, the weight is provided with a roller 14 that rests upon a track 70 beam 15, the ends of which are supported by the cylinders of the pump, or in any preferred way. The piston rod 13 passes through the center of the weight 10—12, which is shown as cast in two parts, 10 and 75 12 one of which is laterally removable. Said parts are secured together by bolts 16. The entire weight may be installed or removed without disturbing the piston rod. Said rod may be enlarged, as shown at 13', and 80 the bore of the weight correspondingly enlarged, to prevent any slippage of the weight upon the rod. The cylinder 17 may be that of any reciprocating pump or air compressor. The valve-operating members 85 50 and 51 may conveniently be mounted on rods 18, 19, secured to projections on or of the weight 10—12. The device 50 is pivoted to a sleeve 52 and the device 51 is pivoted to a sleeve 53 slidable on the rod 19, said 90 sleeves being adjustably connected by a lazy-tong construction 54 and held in fixed position by an arm 55 held by means of a sleeve 56 and set screw 57 fast upon rod 18.

Means should be provided within the 95 steam cylinder for cushioning the piston. I have devised and shown herein, certain means for providing steam cushions for the piston without involving any added clearance during normal operation. The normal 100 stroke of the piston is between the inner ends of the ports 2 and 3.

24 and 25 are inner, yieldable cylinder heads, whose inner faces lie close to the pis-

ton faces at the ends of the stroke. The chambers 26, 27 behind said heads may be closed air tight, but it is deemed better to connect said chambers with the steam supply so that steam at boiler pressure will at all times fill them. The pipes 28 and 29 have this function, being connected to the steam-chest 30. Chambers 26, 27 are provided with drain-cocks 31, 32 for water of condensation.

10 As the piston rod 13 must pass through one of the inner heads, 24, 25, the construction shown is recommended as providing accessible packings for the piston rod. 15 Head 25 is formed with a sleeve 33, threaded on its outer end to receive an internally threaded stuffing-box 34. The sleeve passes slidably through the fixed cylinder head, which is provided with a gland 35.

20 Normally, that is when relative steam and water pressures are normal, the inner heads will be moved but slightly or not at all, at the ends of the piston strokes. When, however, a relative steam pressure increases or the relative water pressure decreases, the piston may be carried farther, in which case it cannot strike the head 24 or 25 but will highly compress the steam between them and will force the head 24 25 or 25 to yield.

25 The initial movement of the piston will cut off the port to which the pipe 28 or 29 is connected, and the steam being thereby confined in the narrow space between the fixed and movable cylinder heads will offer great resistance to continued motion of the piston. In addition, exterior buffers may be provided, for example as shown in the drawing. Heads 20 are carried by heavy 30 rods 21 secured to the weight 10—12. Co-operative cylinders 22 are secured to, or cast integral with, the cylinders 1 and 17. The lengths of the rods 21 are such that when the piston stroke does not exceed 35 normal length, the heads 20 will only slightly enter the cylinders, not sufficiently to cause compression of air therein. The compression will occur whenever the pistons are driven too far either way. Thus 40 the exterior buffers coact with the interior devices before described, and relieve the cylinder heads of a part of the stress set up by compression of steam.

45 The invention is not limited to a weight secured directly to the piston rod. The use of a weight in vertical pumps in which the piston is raised by steam and driven down by a weight, is set forth in a separate application for Letters Patent filed January 16th 50 1909 and bearing Serial No. 473,669.

55 On the steam cylinder any suitable valve gear may be employed. No special valve gear is shown, as this invention does not relate to that portion of the mechanism. 60 The cutoff is to be so adjusted that the

pistons will be driven to the ends of their stroke by the combined forces of steam pressure and momentum of the moving parts.

65 The operation of the pump will be fully understood from what has been said hereinbefore.

I claim:

1. A direct acting steam pump comprising two cylinders, pistons therein, a track 75 above the cylinders bridging the space between the cylinders, an inertia weight between the cylinders, an arm on the weight extending above the track, an anti-friction roller on the arm and resting upon the track thereby suspending and supporting the weight, a piston rod connecting the pistons and extending through the weight, and means connecting the rod to the weight to move the same therewith.

80 2. A direct acting steam pump, comprising cylinders, pistons therein, a piston rod connecting the pistons, an inertia weight connected to and actuated by said rod, means other than said rod for supporting said weight, buffers exterior to the cylinders of the pump, and means carried by the weight co-operating therewith to check the excess movement of the weight.

85 3. A direct acting steam pump or air compressor, comprising steam and pumping cylinders having their pistons connected by a common piston rod, an inertia weight connected to the rod to be moved thereby, buffer members secured to said weight, and 100 co-acting buffer members fixed in position to co-act with said members on the weight to check said weight when the piston stroke exceeds the normal.

90 4. A direct acting steam pump comprising steam and pumping cylinders having their pistons connected by a common piston rod, an inertia weight connected to said rod for movement therewith, air-cushion members fixed in position adjacent the cylinders, and co-acting piston heads carried on the weight in alinement with said air-cushion members and positioned relatively thereto so that when the piston stroke exceeds the normal length, said members will 110 operate to check the movement of the weight.

115 5. A steam pump comprising steam and pumping cylinders having their pistons connected by a common piston rod, an inertia weight connected to and actuated by the piston rod, movable cylinder heads in the steam cylinder spaced from the fixed cylinder heads, steam connections entering said spaces between the fixed and movable cylinder heads at points just at the limit of the movable heads so that the initial movement thereof will cut off the steam from the spaces between the fixed and yieldable heads.

6. A steam pump comprising steam and pumping cylinders having their pistons connected by a common piston rod, an inertia weight independently supported for reciprocation between the cylinders and connected to said rod to be moved thereby, movable heads within the steam cylinder spaced from the fixed cylinder heads, and steam connections entering the space between the fixed 5 and movable heads at a point just inside of the edge of the movable cylinder head when the same is in its normal or most inward position, so that the initial movement of the yielding heads will cut off the steam 10 from the spaces.
7. A steam pump comprising steam and pumping cylinders having their pistons connected by a common rod, an inertia weight supported for independent reciprocation between the cylinders and connected with the piston rod for movement thereby, buffer members secured to the weight, co-acting fixed buffer members adjacent the cylinders to retard the weight when it exceeds its normal 15 movement, movable cylinder heads within the steam cylinder spaced from the ends thereof, and steam connections entering the spaces between the movable and fixed cylinder heads at a point just inside of the edge of the movable heads when in their normal or most inward position, so that the initial movement of the head will cut off the steam and check movement of the piston through compression of the steam in the said 20 spaces.
8. A steam pump comprising cylinders, pistons therein, a piston rod connecting the pistons, an inertia weight connected to and actuated by the piston rod, a steam cylinder having in the ends thereof inner yieldable 25 cylinder heads, the piston rod passing through one of said heads, said head being formed with a sleeve passing through a bore in the fixed cylinder head, packing between said sleeve and the fixed cylinder head, and packing between the piston rod and said sleeve.
9. A steam pump, comprising two cylinders in a horizontal alinement, pistons therein, a piston rod connecting the pistons, an inertia weight intermediate the pistons and through which the piston rod passes, a track for supporting the weight, buffer members secured to the weight, co-acting buffer members fixed in position to co-act with said 30 buffer members when the piston exceeds its normal stroke, yielding cylinder heads within the steam cylinder with spaces between the yielding heads, and the fixed heads and steam connections to said spaces, said steam 35 connection entering the cylinder at such a point that the initial movement of the yieldable heads will cut off the steam from the spaces between the fixed and the yieldable heads.

KENNEDY DOUGAN.
